INTERNAL-COMBUSTION ENGINE.

1,375,651.

Specification of Letters Patent. Patented Apr. 19, 1921.

Application filed March 17, 1920. Serial No. 366,520.

To all whom it may concern:

Be it known that we, VERNON W. BALZER and JOHN MCK. BALLOU, citizens of the United States, residing at Los Angeles, in the county of Los Angeles and State of California, have invented a new and useful Internal-Combustion Engine, of which the following is a specification.

This invention relates to internal combustion engines of the two cycle type.

One of the objects of this invention is to provide a combination rotary intake valve, intake manifold, and exhaust-cam-shaft.

Another object is to reduce the weight of such an engine to make it especially adapted for aeroplanes and similar devices in which such a reduction is very essential.

Another object is to reduce the weight and size of parts in such an engine to make it adaptable for devices in which such a reduction is very essential.

Another object is to provide a light but powerful engine of the two cycle type of internal combustion engines.

Another object is to provide proper lubrication for such engines.

Another object is to provide sure and uniform actions of the different parts of such engines.

Another object is to make the starting of such an engine easy and sure.

Another object is to provide safety means against back-firing into the crank casing of such engines.

Other objects will appear from the following description and appended claims as well as from the accompanying drawing, in which—

Figure 1 is an end elevation of the device partly broken out to show a midsectional view of one of the cylinders.

Fig. 2 is a top plan view of the device partly broken out, showing a midsectional view of one of the cylinders and a portion of the crank shaft in top plan view.

Fig. 3 is a side elevation of the device partly broken out showing a midsectional view of the combination intake valve—intake manifold—and exhaust cam shaft.

The crank case 1 forms the base of the

whole construction of the device. The several cylinders 2 are suitably secured to the crank casing, by screws or any other similar suitable means, not shown in the drawing but easily and clearly understood without further detail illustration of such interconnections. The cylinders 2 are preferably provided with exhaust connecting ends 3. A valve 4 is extended into the exhaust connection 3 for controlling the exhaust from the cylinders. The operating rods 5 are extended into the crank case to come into contact with the cams 29 on the cam shaft 8, see Fig. 3. The housing 6 incloses the cams 29 and the shaft 8, see Fig. 1. The cam shaft is hollow forming at the same time the manifold with the passage 7.

To prevent a damaging of the crank case by a back firing of the charge into the crank case, a safety valve, or a suitable number of such valves, 9 is provided on the case 1, operated by springs 10, or other similar means, see Figs. 1, 2 and 3.

Connecting rods 11 connect the pistons 12 with the crank shaft of the device, see Fig. 1. Two oppositely arranged cylinders naturally work together on the crank shaft on cranks arranged at about 180° on opposite sides of the shaft so that the connecting rods of two pistons in such oppositely arranged cylinders engage on the crank shaft 35 in the manner illustrated in Fig. 2. The cranks 30 and 36 in this case are preferably arranged so close as to necessitate the forming of the crank shaft in the bent form as indicated at 37, to shorten the whole device, each connecting rod naturally just passing the opposite crank while the crank shaft is rotating, as will easily be understood.

The cylinders 2 are provided with extension ends 38 extending and projecting to within the crank case 1. Such extension ends 38 are provided with a suitable number of ports 13 and 14. The pistons 11 naturally come to a position within the extension ends 38 of the cylinders during the rotations of the crank shaft. The ports 13 in the extension ends 38 of the cylinders are so located that they come to be located above the pistons when the pistons are in the in-

nermost positions of their strokes, that is within the extension ends 38.

The chamber 15 within the crank case 1 forms the compression chamber of the device, each stroke to their innermost position of the pistons causes and produces a certain initial compression within the crank case, and any gas introduced into the crank case receives enough compression to have the 10 tendency to escape through the ports 13 to above the pistons in the cylinders 2. During the stroke in the opposite direction, that is toward the outside, this escaped gas is compressed more completely in the cylinders 2 15 above the pistons 12 to be ready for the explosion when the pistons come to the outermost positions, indicated in Fig. 2 in the drawing. The nut 22 is simply a plain sleeve or gland nut into which the spark 20 plug 21 is screwed and which serves to allow the larger valves 4 to be exchanged through such larger opening, possible when such nut is used. The carbureter 23 has communication with the passage 7 in the hollow cam 25 shaft 8, that is the hollow manifold of the device, see Fig. 3. Suitable gears 24 are in engagement with the main shaft 35, so that, on a turning of the main shaft 35, the cam shaft 8 is also turned in suitable relation 30 to the main shaft. The space 25 between the extension ends 38 of the cylinders 2 and the crank case 1 is naturally large enough to allow the gas to pass from the crank case 1 and through the ports 13 into the cylinders 35 when the pistons 12 are in such suitable positions as described above. Slots or ports 26 are provided in the bottom of the crank case 1, see Figs. 1 and 3. Other slots or ports 27 come into alignment with the 40 ports or slots 26 in the case when the pistons are in their outermost positions, at which time a suitable suction is produced within the crank case which causes a suitable amount of gas from the manifold to pass 45 into the crank case. On further rotating, the communication between the crank case and the manifold is naturally shut off, and, by the same rotation of the crank shaft, being interengaged by the gears 24 with the 50 rotating manifold, the drawn-in gas mixture in the crank case is compressed by the pistons coming to their innermost position, as will easily be understood from the description above. At the innermost position 55 of the pistons, the gas mixture is then again allowed to pass over into the cylinders through the ports 13 as described above. Thus operation continues.

Arranging two cylinders on opposite sides 60 of the crank shaft in the manner illustrated and described naturally equalizes the strain of the force on the crank shaft, and arranging such sets of cylinders side by side on the

crank shaft naturally helps to equalize the force of the whole engine. 65

The end of the shaft 35 can naturally be provided with a suitable pin or connecting end 18 to allow the connection of other machinery.

This engine is especially suitable for aeroplanes, inasmuch as this two cycle engine is especially light and at the same time strong. 70

The exhaust valves are normally provided with the springs 28 for normally holding the valves closed so as to allow the gas mixture above the pistons 12 to reach a maximum compression when the pistons come to position illustrated in Fig. 2, that is their outermost position within the cylinders. 75

Having the openings, slots, or ports 26 in the bottom of the crank case makes a draining of the case easy; but it also facilitates the lubricating of the whole engine, since the gas, passing in through such openings, slots, or ports, causes naturally a spraying 85 of any settled lubricant from this lower part of the engine through the whole engine. The possibility of draining makes also a starting easy since it allows the eliminating of excess of gas vapor or other substances, which 90 would tend to make such starting hard at times. It furthermore tends to eliminate the accumulating of oil or other undesired substances in the bottom of the engine during the operation of the engine since the 95 incoming gas always will force such substances up through the engine, eventually through the exhaust, as will easily be understood.

Having thus described our invention, we 100 claim:

1. In an internal combustion engine, a cylinder, a crank case having a port in its side, a cam shaft disposed alongside of the crank case having a passage therethrough forming the manifold of the device and having a port normally shut off from communication with the crank case adapted to communicate with the crank case through the port forming the inlet from the manifold to the engine. 110

2. In an internal combustion engine, a crank case having an inlet port in its bottom side, and a hollow cam shaft disposed alongside of the crank case having a port for 115 communicating with and through the port in the crank case when so operated.

3. In an internal combustion engine, a crank case having an inlet port in its bottom side and having a longitudinal conduit 120 alongside of the crank case, a crank shaft through the crank case practically parallel to the conduit in the case, cylinders disposed on the crank case projecting sidewise from the crank case at about right angles from the 125 crank shaft, the cylinders having extension

ends extending into the crank case, the extension ends of the cylinders having ports at a point within the crank case, pistons disposed in the cylinders so as to come below the ports in the extension ends of the cylinder when in their innermost position in relation to the crank case so that a gas mixture in the crank case can pass over into the cylinders above the pistons when in this position, and a hollow cam shaft disposed in and through the longitudinal conduit in the

bottom of the crank case forming the manifold of the device.

In testimony that we claim the foregoing as our invention we have signed our names 15 in the presence of two subscribing witnesses.
